(57) **CLAIM**

(21) Appl. No.: **29/284,593**

The ornamental design for a shaving head unit, as shown.

(22) Filed: **Sep. 12, 2007**

(30) **Foreign Application Priority Data**

Mar. 20, 2007 (EM) 000691209

DESCRIPTION

(51) **LOC (8) Cl.** **28-03**

FIG. 1 is a perspective view showing my design;

(52) **U.S. Cl.** **D28/50**

FIG. 2 is a front elevational view thereof;

(58) **Field of Classification Search** D28/44-54;

FIG. 3 is a rear elevational view thereof;

30/30, 32, 34.05, 34.1, 34.2, 41-41.9, 44,

FIG. 4 is a right side elevational view thereof;

30/45, 47-51, 57, 58, 526, 527, 532, 533,

FIG. 5 is a left side elevational view thereof;

30/537-540, 346.5, 346.51-346.61, 43-43.92

FIG. 6 is a top plan view thereof; and,

See application file for complete search history.

FIG. 7 is a bottom plan view thereof.
